J. M. Naylor
ATTORNEY.

UNITED STATES PATENT OFFICE

JOHN B. ROSEFIELD, OF PIEDMONT, CALIFORNIA

SPRAYING DEVICE

Application filed March 23, 1929. Serial No. 349,332.

The present invention relates to liquid sprayers, particularly the type employing an air pump of the common type, with siphoning means attached thereto, permitting a ready connection of the pump and siphoning means to ordinary containers of the liquid to be sprayed, thereby doing away with the usual tank that requires filling from another container of the liquid. By employing my device the user of this class of goods is able, therefore, to purchase a less expensive and more effective spraying device.

Another purpose of my invention is to provide a more positive means of feeding the liquid to the siphon system for the prevention of such waste as the present devices on the market entail. I am aware that there are spraying devices now in use which have a pump and siphoning means in combination for adaption to the usual containers of such liquids, but those devices provide a straight siphon tube of a set length; consequently, the operator can only use the sprayer when the depth of the container is greater than the length of the siphon tube, and waste occurs when the container is of greater depth than the length of the siphon tube, due to the fact that the liquid is "out of reach", so to speak, of the intake end of the tube.

With these and other purposes in view, my invention consists of parts and combinations which are hereinafter described, and the novel features thereof pointed out in the claims.

The drawings consist of the following features:

Figure 1 is a longitudinal section through the pump and siphoning means, the parts being shown in elevation.

Figure 2 is an end view of the sprayer with the usual container attached.

There has ever been a demand for an effective sprayer which could be sold separately from a supply tank and one which would be readily adaptable to containers common to the trade, provided with an opening of standard dimensions, threaded in the usual way, to avoid the necessity of filling a supply tank, which has never been the most pleasant task.

Since my invention is provided with a pump,

a standard size threaded cap and a siphoning means permanently joined in proper fixed relation, it is believed some of the difficulties of sprayers now in use have been overcome.

An additional feature of my invention, and an obviously advantageous one, is that by providing a U-shaped tube with its intake end positioned in near relation to the inner top surface of the cap, an operator is able to turn the container upside down, and thereby be assured of a free delivery of fluid with each stroke of the pump. I have also provided means whereby the small amount of fluid that would naturally be siphoned, will be caught in a drip cup, and siphoned off by the first one or two strokes of the pump.

One form of my invention is illustrated in the accompanying drawings, in which 1 indicates a standard hand operated air pump, equipped with the usual piston 2, secured to a piston rod 3 which extends through the cap of the pump and is connected to the customary operating handle 4. The exhaust end of the pump is closed in by the wall 5, which is provided with a port 6, directly at the outlet end of the supply siphon tube 7, and the outlet end of the overflow siphon tube 8. The siphon tube 7 is substantially U-shaped and is imperforate between its ends, its intake end is disposed slightly clear of the inner surface of the top of the threaded container closure cap 9. In the present disclosure of my invention I have shown the sprayer attached to a suitable container 10. The overflow siphon tube 8, it will be noted, communicates with the drip-cup 11, which is secured to the exhaust end of the air pump 1, and its intake end is angled to permit siphoning off of the overflow which may accumulate in the drip cup when the sprayer is inverted and put into operation. This tube 8, may also have a substantially horizontal intake end disposed slightly above the bottom of the drip cup, and may be of other constructions with the breadth of the appended claims.

The operation of my sprayer is carried out substantially as follows: The sprayer is attached to a container of the liquid desired to be sprayed by means of the threaded closure cap 9, and the whole then inverted. The

liquid automatically fills the top (now the bottom) of the closure cap 9, and with each stroke of the pump, is drawn into the intake end of the supply siphon tube 7, from which it is blown by the exhaust air through the port 6, assuring equality of supply until the contents of the container are substantially totally exhausted. Further, the U-shaped tube tends to prevent accidental escape of the liquid from the container through the discharge opening of the tube while the device is being handled. With the container partly filled with liquid, sudden movements of the container causes the liquid to surge therein. This surging of the liquid tends to squirt the same through the discharge opening. With a short, straight discharge tube, the tendency to squirt would be considerable; on the other hand, with the comparatively long U-shaped discharge tube, the tendency to squirt through surging would be lessened, as this tube would trap the liquid.

When the sprayer and the filled can are inverted, there will be a natural siphoning or flow of the liquid through the tube 7, without a stroke of the pump; which small quantity would ordinarily drip onto the ground or floor as the case might be, causing objectionable stains. I have overcome this by providing the drip cup 11 and the short siphon tube 8, by which the overflow is automatically siphoned off with the first one or two strokes of the pump.

Modifications of my invention may be used without departing from the principle of my invention as described in the appended claims, without the loss of any of the material benefits to be derived from its use.

What I claim as new and desire to secure by Letters Patent is as follows:

1. A spraying device comprising an air pump provided with a suitable discharge, a cap secured to said pump for attachment to a suitable container, a substantially U-shaped siphon tube imperforate between its ends and having its discharge end extending through said cap and adjacent said pump discharge and its intake end in close relation to the inside of said cap, a drip cup secured to said pump opposite said cap and also opposite the discharge end of the U-shaped siphon, and a second siphon tube with its intake end in communication with said drip cup and exhaust end adjacent said pump discharge.
2. A spraying device comprising an air pump provided with a suitable discharge, a cap secured to said pump for attachment to a suitable container, a substantially U-shaped siphon tube imperforate between its ends and having its exhaust end extending through said cap and adjacent said pump discharge, a drip cup secured to said pump opposite said cap and also opposite the discharge end of the U-shaped siphon, and a second siphon

tube in communication with said drip cup and said pump discharge.

3. A spraying device comprising an air pump provided with a suitable discharge, closure means for a suitable container secured to said pump, a substantially U-shaped siphon tube having one end extending through said closure means and in aspirating relation to said pump discharge, a drip cup secured to said pump opposite said closure means, and a second siphon tube with its intake end in communication with said drip cup and its discharge end in aspirating relation to said pump discharge.

4. A spraying device comprising an air pump provided with a suitable discharge, a cap secured to said pump for attachment to a suitable container, a drip cup secured to said pump opposite said cap, and means for simultaneously siphoning fluid to the pump discharge from both the drip cup and a suitable container attached to said cap.

5. A spraying device comprising an air pump provided with a suitable discharge, a container secured to said pump, a drip cup secured to said pump opposite said container, and means for simultaneously siphoning the fluid to the pump discharge from both the drip cup and the said container.
